ATTORNEY.

UNITED STATES PATENT OFFICE.

JAMES COWLING, OF GALENA, ILLINOIS.

THERMOMETER.

1,038,530.

Specification of Letters Patent. Patented Sept. 17, 1912.

Application filed January 11, 1911. Serial No. 602,126.

To all whom it may concern:

Be it known that I, JAMES COWLING, a citizen of the United States, residing at Galena, in the county of Jo Daviess and State of Illinois, have invented certain new and useful Improvements in Thermometers, of which the following is a specification.

My invention relates to thermometers with special reference to those of great size and length, and the leading object is to economize in the operating fluid and still maintain its sensitiveness and accuracy.

It consists in inserting in the fluid register tube a spacing member or body which shall largely fill said tube.

It further consists in providing a fluid containing bulb preferably formed of metal which shall present a large surface to the atmosphere and still largely economize in fluid whereby the same sensitiveness is maintained as in a small bulb with a small amount of fluid.

These features will be fully developed and presented in detail in the following specification when considered in connection with the drawings accompanying the same and forming a part hereof in which—

Figure 1 is a perspective view of my device with the box shown in dotted lines. Fig. 2 is a cross section through line 2—2 of Fig. 1, looking downward. Fig. 3 is a cross section of Fig. 1 on line 3—3. Fig. 4 is a plan view of the rest for the inner member. Fig. 5 is a perspective view of the box that incases the bulb of the fluid receptacle.

Like characters of reference denote corresponding parts in each of the drawings.

Referring to the drawings, 2 designates the register plate which is provided with a longitudinal opening 3 running nearly the length of the plate. Said plate is supplied with the usual figures represented in this drawing, the degrees of temperature from 30° below zero to 160° above. The same 45 may be placed upon both sides of the plate so that it may be read by a party approaching the thermometer from opposite directions. It is manifest that this plate may have on it the registration of more or less 50 number of degrees according to the surroundings in which the thermometer is to be used. In the opening 3 of the registration plate 2 is secured, in any well known manner, the register tube or member 4 which 55 is sealed at the top 5 in the usual manner. This tube is secured in a bulb receptacle 6

by inserting the lower end in the upper end of the receptacle 6 and then surrounding it with packing, (preferably rubber) and securing it with a nut 10, whereby the tube 60 will be sealed air tight in the receptacle 6.

For the purpose of presenting a large surface to the atmosphere and maintaining the greatest sensitiveness, the receptacle 6 is preferably made of thin sheet copper and 65 enlarged by inserting in the body portion a plurality of tubes or compartments 15. By this mode of construction there is exposed to the atmosphere a very large surface with only a small amount of fluid. The receptacle is secured in a box 16 by a set screw 18 70 through openings 20, which box is provided with openings 22.

Within the tube 4 is set a spacing member 25 which is of such size as to largely fill 75 the tube 4. The member, if hollow, is sealed at both ends and held in the center of the tube 4 by wires 26 around the member with points 28 extending out from the member and engaging the inner side of the tube 80 4. This member rests upon a cross piece 30 that is secured within the body of the fluid receptacle 6.

The mode of operating my device is substantially as follows. The member 25 is 85 sealed at both ends, if it be a hollow tube, and inserted into the tube 4 till it rests on the cross piece 30 with the points 28 of the wires 26 engaging the inner sides of the tube 4. This will leave only a small space 90 in the tube 4 around the member 25. The fluid is introduced into the tube 4 at the top 5 and continued till the receptacle 6, with the compartments 15 are filled and around the member 25 till the fluid registers the surrounding temperature of the atmosphere 95 then the end 5 is sealed. The thermometer will then operate in the same manner as other thermometers.

It will be seen by this mode of construction, with the member 25 nearly filling the tube 4 and the bulb with the various compartments exposing a large surface of thin copper to the atmosphere, that the delicate sensitiveness of the ordinary bulb will be 100 maintained, also great economy in fluid and the thermometer may be made in two parts and of many feet in length.

Having now described my invention what I claim, and desire to secure by Letters 110 Patent is:—

A thermometer, comprising a slotted

registering plate, a thermometer tube arranged longitudinally in the slot of said plate and projecting beyond the front and rear faces of the latter, a fluid receptacle provided with separated fluid compartments, said receptacle being threaded at its upper end, packing between the thermometer tube and fluid receptacle, a nut embracing the thermometer tube and securing the same to the threaded upper end of the fluid receptacle, a filler member arranged within the thermometer tube and extending substan-

tially the entire length thereof and being substantially evenly spaced from the walls thereof, and a member extending across the thermometer tube and supporting the lower end of the filler member.

In testimony whereof I affix my signature in presence of two witnesses.

JAMES COWLING.
